FIRE ALARM

Jens K. Grondahl, Red Wing, Minn.

Application October 16, 1937, Serial No. 169,446

9 Claims. (Cl. 179—5)

This invention relates to a fire alarm connected with a telephone receiver.

An object of the invention is the provision of a fire alarm which may be readily attached or detached from a telephone receiver known as the "French" type and in which a spring-pressed plunger controlling a switch is held in an inoperative position by an arm which is retained in an operative holding position by a fusible element, said arm also retaining a motor against operation which when released will actuate a mechanism for advising the telephone operator at the switchboard that the building in which the telephone is located is on fire.

Another object of the invention is the provision of an attachment for a French telephone for maintaining a switch-controlling plunger in an inoperative position until the device is released by the melting of a fusible element because of intense heat in the neighborhood, said device including a motor for operating a phonograph located adjacent the mouth-piece of the receiver or for giving a signal adjacent the mouth-piece so that the telephone operator at the switch-board will be advised that a portion of the building is on fire where the receiver is located so that such operator can notify the proper authorities of the condition.

A further object of the invention is the provision of a device for releasing the usual spring-pressed plunger of a French telephone for closing the circuit, with means for giving audible signals for advising a telephone operator that the building in which the telephone is located is on fire.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a front view showing my fire alarm attached to a telephone receiver,

Figure 2 is a plan view of the same,

Figure 3 is an end view,

Figure 4 is a plan view of the signalling means showing the cover partly broken away,

Figure 5 is a fragmentary enlarged side view showing the stop in locked position and retaining the mechanism against operation,

Figure 6 is a vertical section of the alarm shown in Figure 4,

Figure 7 is a horizontal section through the bracket for supporting the alarm, and

Figure 8 is a vertical section of a modified form of the alarm.

Referring more particularly to the drawings, 5 10 designates a base member of a French telephone having a post 11 rising from the base member and provided with pairs of upstanding fingers 12 which receive the shank or body portion 13 of a receiver, generally designated by the numeral 14.

The body portion is received between the pairs 15 of fingers 12 and normally rests upon the top or supporting head 15 carried by the upper end of a spring-pressed plunger (not shown) which controls the closing of the switch when the receiver 14 is removed and the plunger rises in the post 11. The body is provided with a mouth-piece 16 and an ear-piece 17. The parts just described are well known and form no part of the present 20 invention.

The bracket, generally designated by the numeral 20, is provided with a U-shaped member and includes an arm 24, a bridging portion 25 and a depending arm 26. The members 24 and 26 25 are disposed in parallel relation and are spaced sufficiently apart so that the bracket may be pressed down over the portion 27 upon which rests the head 15. The member 27 is formed integrally with the post 11. The inner faces of the members 24 and 26, as shown at 28, are provided with rubber pads which frictionally grip the side walls of the upper end of the post 11 for aiding in maintaining the bracket 20 in position.

The bracket is provided with an offset arm 29 having the curved member 30 which engages around a casing 31 and is rigidly secured thereto for supporting said casing.

A lever 35 is normally located in flat contact with the arm 29 on the bracket 20 and has secured thereto a rock shaft 36 which is rockably mounted in the sleeve 37 connected to the bracket 20 and forms a bearing for the rock shaft 36.

A crank 38 is secured to the inner end of the shaft 36. A finger 39 is secured to the outer free end of the crank and normally engages the head 15 of the receiver for maintaining said head in an inoperative position, as shown in Figs. 1 and 3. The lever 35 is provided with a perforation 40 while the arm 29 is provided with a perforation 41 and these perforations are placed in alignment with each other and a fusible pin 42 is inserted in these perforations for locking the lever 35 to the arm 29 so that the finger 39 will be maintained in an operative position for retaining the head 15 45 50 55 50 55

depressed. As shown in Fig. 1 the receiver 14 is placed on the bridging member 25 so that when the lever 35 is released the head 15 may be raised in the usual manner because the receiver is anchored above said head.

The casing 31, as has been previously explained, is supported by the curved portion 30 of the arm 29 and the outer face 43 of said casing which is in the form of a removable cover, is held directly beneath the mouthpiece 16 of the receiver. The casing is also provided with a removable bottom 44.

A spring motor 45 is located within the casing 31 and a winding knob 46 is secured to the shaft 47 which is connected with a spring motor in the usual manner. The knob 46 is provided with a slot 48 which is adapted to be received by some suitable tool for winding the motor. Connected with the motor is a train of gears, generally designated by the numeral 50, for operating a governor composed of the weighted members 51 and 52. Each weighted member is supported in the block 53 by means of a rod 54 upon which is mounted a coil spring 55 having one end in engagement with a block while the other end is in engagement with a nut 55a. When the nuts are adjusted one way or the other the governor will control the speed of the motor in accordance with such adjustment. In other words, when the spring member is tightened the speed of the motor will be increased while when the pressure on the spring is released the speed will be lowered. Naturally both nuts will have to be adjusted the same distance.

The usual ratchet wheel 56 and pivoted pawl 56a are employed for preventing unwinding of the spring when the motor is being wound. A spring 57 carried by the casing is adapted to maintain the pawl 56 in engagement with the teeth of the ratchet 55.

The shaft 47 adjacent the closure 43 is provided with a shoulder 58 on which rests a washer 61. Upon this washer is mounted one end 62 of an arm 63 and a nut 64 is threaded onto the upper end of the shaft 47 for securing the member 62 rigidly to the shaft. The outer reduced end 65 of the shaft 47 is mounted in a bearing 66 formed on the cover 43.

The inner face of the cover 43 is provided with a plurality of lips 67 which are adapted to be engaged by the free end of the arm 63 when said arm is rotated so that these lips will be periodically engaged during rotation of the arm and give to the operator through the diaphragm 68 of the mouth-piece 16 a predetermined call or signal which will indicate that the building is on fire so that the operator may send in the alarm. The shape and size of the members 67 may be varied to give different calls. However, since the arm 63 rotates continuously until the motor 45 has been unwound the operator will have plenty opportunity to determine what the call is and where it is from.

Referring more particularly to Fig. 8 it will be seen that a modified form of the annunciator is provided in which the shaft 41a is connected to a disc 70 and provided with grooves of the usual type of phonograph record.

An arm 71 is secured to the usual top 72 on the casing or box 31a and the arm 71 supports a needle 73 which has a stylus 74 engaging the record 70. The outer end of the needle or wire 73 is in contact with the diaphragm 68 of the telephone receiver.

As the disc 70 is revolved and the needle 73

moves over the record it will either produce sound or tell the operator that a fire is located at a certain residence.

The fire alarm described above is such that it is merely an attachment for the telephone receiver and must be removed before a call can be put through. In other words, the frame 20 may be disengaged from the post 11 while the plunger 15 is maintained by the finger of the operator in lowered position, since the frame is merely frictionally engaged on the post.

The alarm may be applied to the receiver when the house is being left vacant and as soon as the owner returns the alarm may be removed and the telephone receiver placed in its usual position. The casing 31 or 31a carries a shaft 15 operated by a knob or finger-piece 76. The inner end of the shaft is provided with a pawl 77 which is adapted to engage the governor including the arms 51 and 52, and thereby retain the motor 45 against operation.

The knob 76 is held in position by means of a pin 78 which engages the free end 79 of the lever 35. As long as the fusible element or pin 42 has locked the lever 35 to the arm 29 of the bracket 20, the free end 79 of said lever will engage the pin 78 and prevent the governor from permitting the motor to be operated.

I claim:

1. In a telephone receiver having a post and a spring-pressed circuit closing plunger in the post, a bracket removably mounted on the post and adapted to support the receiver in an inoperative position above the plunger, a lever pivotally mounted on the post, a finger on the lever engaging the plunger and retaining the same in an inoperative position, a fusible pin connecting the lever to the bracket against movement, an alarm carried by the bracket and disposed adjacent the mouthpiece of the receiver, means for operating the alarm and means engaged by the lever for retaining the operating means for the alarm against movement until the fusible pin releases said lever.

2. In a telephone receiver having a post and a spring-pressed circuit closing plunger in the post, a bracket removably mounted on the post and adapted to support the receiver in an inoperative position above the plunger, a lever pivotally mounted on the bracket and having means engageable with the plunger for normally depressing said plunger, a fusible pin for retaining said lever against movement to hold the plunger-engaging means on the lever in an operative position, an alarm associated with the mouth-piece of the receiver, means for operating the alarm, and means for retaining the operating means against action, said lever engaging the retaining means until the fusible pin releases the lever.

3. In a telephone receiver having a post and a spring-pressed circuit-closing plunger in the post, a bracket removably mounted on the post and adapted to support the receiver in an inoperative position above the plunger, movable means on the bracket for retaining the plunger depressed, a fusible element for retaining the movable means in operative depressing relation with the plunger, an alarm on the bracket and disposed adjacent the mouthpiece of the receiver, operating means for the alarm, cooperating means on the operating means and the movable means for retaining said operating means against action until the fusible element releases the movable means.

4. In a telephone receiver having a post and a

spring-pressed plunger for closing or opening a circuit, a bracket removably mounted on the post and supporting the receiver above the outer end of the plunger, movable means on the bracket for retaining the plunger inoperative, a fusible element for holding the movable means against the spring-pressed plunger, an alarm adjacent the mouth-piece of the receiver including a motor for actuating the alarm, means for retaining the motor against operation, said movable means engaging the retaining means and adapted to release said retaining means when the fusible element has been melted.

5. In a telephone receiver having a post and a spring-operated circuit closer, means for supporting the receiver in an inoperative position above the closer, a lever removably mounted on the post and having means for retaining the closer open, an alarm adjacent the mouth-piece of the receiver, means for actuating the alarm, said lever retaining the actuating means against operation, a fusible element for retaining the lever against actuation by the spring-operated closer.

6. In a telephone receiver having a post and a spring-operated circuit closer, a bracket having spring arms for removably connecting the bracket to the post, said bracket having a support for the receiver for maintaining said receiver out of contact with the closer, movable means on the bracket for retaining the closer in open position, a fusible element for maintaining the movable means in an operative position on the bracket, an audible signal supported by the bracket adjacent the mouthpiece of the receiver, means for operating the signal and cooperating means on the operating means and the movable means for holding the operating means against actuation.

7. In a telephone receiver having a post and a spring-operated circuit closer, a detachable

means mounted on the post for supporting the receiver out of contact with the circuit closer, movable means on the detachable means for retaining the closer open, a fusible element for holding the movable means against operation, an alarm adjacent the mouthpiece of the receiver and having a rotary element, means for rotating said element, the movable means retaining the rotating means against operation, and means in the alarm and periodically engaged by the rotary element for producing a signal which will indicate to the telephone operator that a building is on fire.

8. In a telephone receiver having a post and a spring-operated circuit closer, a detachable bracket mounted on the post and having a support for maintaining the receiver out of contact with the closer, a movable means on the bracket for retaining the closer open, a fusible element for holding the movable means against operation, an alarm adjacent the mouth-piece of the receiver and having a rotary element, means for rotating said element, the movable means retaining the rotating means against operation, and means in the alarm and periodically engaged by the rotary element for producing a signal which will indicate to the telephone operator that a building is on fire.

9. In a telephone receiver having a spring-operated circuit closer normally held inoperative by the weight of the receiver, means for supporting said receiver out of operative relation with the circuit closer, an alarm adapted to influence the mouth-piece of the receiver, means for operating the alarm and means retaining the last mentioned means and the closer in an inoperative position and including a fusible means.

JENS K. GRONDAHL.
